UNITED STATES PATENT OFFICE

2,600,669

TUBE SLOTTING MACHINE

Clifford L. McAuliffe, San Pedro, Calif.

Application October 1, 1949, Serial No. 119,129

7 Claims. (Cl. 164—42)

1

This invention relates to a tube slotting machine, and particularly a machine which will slot the end of pipe, and particularly sheet metal pipe, so that the cut or slotted ends of the pipe can be flared outwardly for the purpose of attaching a short length of pipe to a wooden concrete form.

An object of my invention is to provide a novel tube slotting machine which will cut or slot the end of a length of pipe, and will regularly space these cuts to form adjacent tips on the end of the pipe.

A feature of my invention resides in the novel means whereby the length of pipe is clamped in the machine, and is intermittently rotated by the machine. The cutting or slotting of the tube is accomplished while the tube is stationary.

Still another object of my invention is to provide a novel tube slotting machine, which will automatically space the cuts in the end of the tube and will quickly and effectively accomplish the required cutting or slotting of the pipe.

Other objects, advantages and features of the invention may appear from the accompanying drawing, the subjoined detailed description and the appended claims.

In the drawing

Figure 1 is a side elevation of my tube slotting machine.

Figure 2 is a side elevation of the machine taken of the side opposite of that shown in Figure 1.

Figure 3 is a top plan view of my machine.

Figure 4 is an enlarged fragmentary sectional view taken on line 4—4 of Figure 3.

Figure 5 is a fragmentary view taken in the direction of line 5—5 in Figure 4.

Figure 6 is a fragmentary view taken in the direction of line 6—6 in Figure 4.

Referring more particularly to the drawing, the numeral 1 indicates a frame, preferably built up of structural parts and sufficiently rigid to support the various parts thereon, which will be subsequently described. A motor 2 (preferably electric) is mounted on the frame 1, and this motor drives the gear box 3 through the belt 4, or other suitable drive means. The pulley 5, which is driven from the gear box 3, drives the power shaft 6 through the belt 7, or other suitable drive means. The power shaft 6 is suitably journaled in the frame 1 in a manner which is usual and well known in the art. A cutter or shears 8 is mounted on the top of the frame 1 in the following manner:

The one arm of the shears 9 is bolted to the

top of the frame 1, as shown at 10. The movable arm 11 of the shears 8 is continuously reciprocated by a cam drive from the power shaft 6, and this drive includes a cam 12 fixedly attached to the shaft 6. A strap 13 surrounds the cam 12, and is journaled on the periphery of the cam in the usual manner. A pitman 14 extends from the strap 13 to the arm 11, and the pitman may be adjusted in any one of the holes 15 in the arm. The stroke of the arm 11 may thus be changed as desired. A knurled drum 16 is mounted on the shaft 17, and this shaft is journaled in the frame 1, and projects horizontally from the frame.

15 The shaft 17 and the drum 16 are intermittently rotated by a suitable pawl and ratchet or escapement gear, as follows:

A second cam 18 is attached to the power shaft 6, and is thus continuously rotated. A strap 19 encircles the cam 18, and a pitman 20 extends from the strap 19 and is pivotally secured to an arm 21. The arm 21 is pivotally secured to the frame 1 at its inner end, and a connecting rod 22 is pivotally attached to the outer end of said arm. 20 The upper end of the connecting rod 22 is pivotally secured to an arm 23, which is journaled on the shaft 17. The arm 23 carries a pawl 24, which engages the gear 25 on the shaft 17. The pawl 24 drives the gear 25 in one direction of movement of the arm 23, and escapes the gear in the opposite direction of movement of the arm 23, therefore, the shaft 17 and the drum 16 will be rotated intermittently.

To hold the tube 26 tightly in engagement with the drum 16, I provide a knurled roller 27, which is pressed against the drum 16 in the following manner:

The roller 27 is eccentrically mounted on a shaft 28, which is journaled on top of the frame 1. An arm 29 protrudes from the shaft 28, and a rod 30 extends from this arm to a foot lever 31, journaled on the lower end of the frame 1. By stepping on the foot lever 31, the shaft 28 will be partially rotated, thus moving the roller 27 away from the drum 16 and permitting tube 26 to be positioned so as to be cut by the shears 8. A spring 28' bears against a projecting finger 29' on the shaft 28, thus tending to rotate said shaft and press the roller 27 against the drum 16, thereby clamping the tube 26 in position to be cut by the shears 8 and to be intermittently rotated, as described above.

An adjustable stop 32 is mounted on top of the frame 1 and this stop is positioned adjacent the shears 8 and is engaged by one end of the tube 26

thus determining the length of the slot or cut which is made by the shears in the tube.

Having described my invention, I claim:

1. A tube slotting machine comprising a frame, a motor mounted on said frame, shears mounted on said frame, drive means extending from the motor to the shears to continuously reciprocate said shears, a drum positioned below the shears and rotatably mounted in said frame, an intermittent drive means extending from the motor to said drum, and tube clamping means adjacent said drum and spaced therefrom and adapted and arranged to press a tube against said drum, said shears being positioned between said drum and said clamping means and parallel to the axis of the drum.

2. A tube slotting machine comprising a frame, a motor mounted on said frame, shears mounted on said frame, drive means extending from the motor to the shears to continuously reciprocate said shears, a drum positioned below the shears and rotatably mounted in said frame, an intermittent drive means extending from the motor to said drum, a tube clamping roller mounted adjacent said drum and extending parallel thereto, and manually actuated means engaging said roller to press said roller towards said drum, the tube to be cut being clamped between the roller and the drum, said shears being positioned between said drum and said clamping roller and parallel to the axis of said drum.

3. A tube slotting machine comprising a frame, a motor mounted on said frame, shears mounted on said frame, drive means extending from the motor to the shears to continuously reciprocate said shears, a drum positioned below the shears and rotatably mounted in said frame, an intermittent drive means extending from the motor to said drum, a shaft journaled on the frame, a roller eccentrically journaled on the shaft, and manually actuated means engaging and rotating said shaft to press the roller towards the drum and clamp a tube therebetween, said shears being positioned between said drum and said clamping roller and parallel to the axis of said drum.

4. A tube slotting machine comprising a frame, a motor mounted on said frame, shears mounted on said frame, a cam drive mounted on said frame and means connecting the cam to said shears to reciprocate the shears, a drive extending from the motor to the cam, a drum journaled on the frame below the shears, intermittent drive means extending from said motor to the drum, a clamping roller mounted on the frame adjacent said drum, manually actuated means to press said roller towards the drum and clamp a tube between the roller and the drum, said shears being positioned between said drum and said clamping roller and parallel to the axis of said drum.

5. A tube slotting machine comprising a frame, a motor mounted on said frame, shears mounted on said frame, a cam drive mounted on said frame and means connecting the cam to said shears to reciprocate the shears, a drive extending from the motor to the cam, a drum journaled on the frame below the shears, a second cam

journaled on the frame, drive means extending from the motor to the second cam, and an escape-
ment drive extending from the second cam to
said drum to intermittently rotate said drum, a
5 roller adjacent said drum, and manually actuated
means to press said roller towards the drum
and hold a tube therebetween, said shears being
positioned between said drum and said clamping
roller and parallel to the axis of said drum.

10 6. A tube slotting machine comprising a frame, a motor mounted on said frame, a power shaft journaled on the frame, drive means extending from the motor to the power shaft, shears mounted on the frame, cam means on the power shaft, and a connecting rod extending from the cam
15 means to the shears whereby the shears are continuously reciprocated, a drum journaled on the frame below the shears, a second cam on the power shaft, an intermittent drive means connecting the second cam and the drum whereby
20 said drum is intermittently rotated, a clamping roller adjacent said drum, and manually actuated means pressing said roller towards the drum to clamp a tube therebetween, the axis of said
25 roller parallel to the axis of said drum, said roller adapted to mount a tube with its axis parallel to that of the roller and the drum, said shears positioned between the axis of the drum and the roller and in the plane thereof and adapted to slot the end of a tube.

30 7. A tube slotting machine comprising a frame, a motor mounted on said frame, a power shaft journaled on the frame, drive means extending from the motor to the power shaft, shears mounted on the frame, cam means on the power shaft, and a connecting rod extending from the cam
35 means to the shears whereby the shears are continuously reciprocated, a drum journaled on the frame, a second cam on the power shaft, an intermittent drive means connecting the second cam and the drum whereby said drum is intermittently rotated, a clamping roller mounted adjacent said drum, the axis of said roller parallel to the axis of said drum, said roller adapted
40 to mount a tube with its axis parallel to that of the roller and the drum, said shears positioned between the axis of the drum and the roller and in the plane thereof and adapted to slot the end of a tube, a shaft on which the clamping
45 roller is mounted, means journaling the last named shaft on the frame, a foot lever and a link connecting the foot lever and the last named shaft whereby said shaft is rotated to move said roller towards the drum, and clamp a tube there-
50 between.
